(57) **CLAIM**

The ornamental design for a display screen or portion thereof with animated graphical user interface, as shown and described.

DESCRIPTION

FIG. 1 is a front view of a first image of a display screen or portion thereof with animated graphical user interface showing a first embodiment of the claimed design;

FIG. 2 is a front view of a second image thereof;

FIG. 3 is a front view of a third image thereof;

FIG. 4 is a front view of a fourth image thereof;

FIG. 5 is a front view of a fifth image thereof; and,

FIG. 6 is a front view of a sixth image thereof.

FIG. 7 is a front view of a first image of a display screen or portion thereof with animated graphical user interface showing a second embodiment of the claimed design;

FIG. 8 is a front view of a second image thereof;

FIG. 9 is a front view of a third image thereof;

FIG. 10 is a front view of a fourth image thereof;

FIG. 11 is a front view of a fifth image thereof; and,

FIG. 12 is a front view of a sixth image thereof.

FIG. 13 is a front view of a first image of a display screen or portion thereof with animated graphical user interface showing a third embodiment of the claimed design;

FIG. 14 is a front view of a second image thereof;

FIG. 15 is a front view of a third image thereof;

FIG. 16 is a front view of a fourth image thereof;

FIG. 17 is a front view of a fifth image thereof; and,

FIG. 18 is a front view of a sixth image thereof.

FIG. 19 is a front view of a first image of a display screen or portion thereof with animated graphical user interface showing a fourth embodiment of the claimed design;

FIG. 20 is a front view of a second image thereof;

FIG. 21 is a front view of a third image thereof;

FIG. 22 is a front view of a fourth image thereof;

FIG. 23 is a front view of a fifth image thereof; and,

FIG. 24 is a front view of a sixth image thereof.

(Continued)

FIG. 25 is a front view of a first image of a display screen or portion thereof with animated graphical user interface showing a fifth embodiment of the claimed design; FIG. 26 is a front view of a second image thereof; FIG. 27 is a front view of a third image thereof; FIG. 28 is a front view of a fourth image thereof; FIG. 29 is a front view of a fifth image thereof; and, FIG. 30 is a front view of a sixth image thereof. FIG. 31 is a front view of a first image of a display screen or portion thereof with animated graphical user interface showing a sixth embodiment of the claimed design; FIG. 32 is a front view of a second image thereof; FIG. 33 is a front view of a third image thereof; FIG. 34 is a front view of a fourth image thereof; FIG. 35 is a front view of a fifth image thereof; and, FIG. 36 is a front view of a sixth image thereof. The outermost broken lines in the figures show a display screen or portion thereof and form no part of the claimed design. In each embodiment, the appearance of the images transitions sequentially between the images shown in FIGS. 1-6, FIGS. 7-12, FIGS. 13-18, FIGS. 19-24, FIGS. 25-30, and FIGS. 31-36, respectively. The process or period in which one image transitions to another forms no part of the claimed design.
